PORTABLE RADIO EQUIPMENT

Walter S. Harmon, Los Angeles, Calif., assignor,
by mesne assignments, to Hazeltine Research,
Inc., Chicago, Ill., a corporation of Illinois

Application April 4, 1946, Serial No. 659,470

4 Claims. (Cl. 250—14)

1

This invention relates to radio receiving equipment, and particularly to antenna arrangements for radio receivers of the portable type. In equipment of this nature the antenna must be capable of efficient performance when the set is in use, and yet be capable of being stowed in such a way as not to interfere with the requirements of transportation when the set is carried from place to place. In equipment which is operable from the power supply mains, it is also desirable to provide some way of stowing the power cord when the set is being carried about. All of these requirements must be met without in any way detracting from the appearance of the equipment, or from its operability by relatively unskilled persons.

It is accordingly an object of my invention to provide an antenna structure for portable radio sets which is completely contained within the case or cabinet, but which can be readily moved into a configuration which will allow it to function at maximum efficiency. An additional object is to provide such a structure which will give ready access to a power cord when the antenna is moved to its operating position. A still further object is to provide an antenna which, when used with a case or cabinet of suitable construction, will operate without being moved from its enclosed position, especially in localities where radio signal strengths are high.

It is also an object of my invention to achieve the above results by a construction which, while simple and relatively inexpensive to manufacture, is extremely rugged and dependable in operation.

In accordance with a particular form of the invention, there is comprised in portable radio equipment a case, a chamber within that case providing stowage room for a power cord, the case being apertured to provide access to the chamber. A closure panel is hingedly connected to the case for movement between positions in which it closes the aperture of the case and to which it extends outwardly therefrom. The radio equipment also comprises a rod-like antenna element pivotally mounted upon that surface of the closure panel which faces inwardly of the case when the panel is in aperture-closing position. The pivotal mounting of the rod-like antenna element is spaced from the hinge connection between the closure panel and the case and the pivotal axis of the antenna element is substantially perpendicular to the axis of the closure panel.

The above-mentioned and other objects and

advantages of my invention will best be understood from the following detailed description of a preferred embodiment of my invention, reference being made to the accompanying drawings, in which

5 Figure 1 is a perspective view of a portable radio set embodying my invention,

Figure 2 is a fragmentary view in elevation, and to a somewhat larger scale, of a portion of 10 the device shown in Figure 1,

Figure 3 is a fragmentary sectional view, taken on the line 3—3 of Figure 4, and

Figure 4 is a fragmentary sectional view taken on the line 4—4 of Figure 2.

15 Referring now to Figure 1 of the drawings, the numeral 10 designates the case of a portable radio receiving set of the kind to which my invention is particularly applicable, provided with the usual carrying handle 12. Case 10 is here

20 shown as formed of metal, although it may be made of wood, plastics or other suitable materials. The back plate 14 of the case is provided with an opening 16 which gives access to the interior of the case in which are contained the

25 receiver chassis, and either a power supply cord and its plug 28 or the usual complement of self-contained batteries, or both. A panel 18 is connected to the lower edge of opening 16, as by a hinge 20, and forms a movable closure for said

30 opening, as well as providing a support or shelf for certain parts to be described hereinafter. Pairs of links 22 are pivotally connected to case 10 and to panel 18 to limit its opening movement to ninety degrees. A finger hole 24 may be

35 formed in panel 18 to facilitate moving it from its closed position, and is desirably covered, as by a box-like formation 26, to render the case dustproof when panel 18 is closed, and to limit the amount a finger can be inserted through the

40 hole.

As best shown in Figures 2 and 4, there is secured to panel 18 a support block 32 which pivotally mounts an antenna of the conventional

45 buggywhip type, designated by numeral 30, and comprising a plurality of telescoping sections, as is well known in the art. Block 32 is channel-shaped in horizontal section (Figure 4), and the lower end 34 of antenna 30 (which end may be rounded as shown in Figure 3) is pivotally secured

50 between the legs of the channel by a pivot pin 36. In order to provide sufficient friction at the pivot to maintain antenna 30 in its desired position, the body of block 32 may be bored out as at 38 (Figure 3), and a compression

55 spring 40 and a friction block 42 inserted in the

bore, so as to press against the end 34 of the antenna. A clip 44 may be secured to panel 18 at a point spaced from block 32, and is adapted to receive the outer end of antenna 30 when the latter is pivoted from its erect or vertical position to the dashed line position of Figures 1 and 2.

It will be understood that a suitable connection is provided from antenna 30 or block 32 to the receiver contained in case 10. Hence, all that is necessary to put the antenna in operation is to open the closure panel 18, swing antenna 30 to its vertical position as in Figure 1, and, if desired, extend one or more of its collapsible sections. The location of block 32 on panel 18 assures that the antenna is adequately spaced from the case 10 to prevent shorting the antenna circuit if case 10 is of metal. In the event that panel 18 is also of metal, block 32 and clip 44 are preferably insulated therefrom, as by insulation 48 and 46 respectively. The reason for insulating clip 44 from panel 18, even though antenna 30 is disengaged from the clip in its normal position of use, is to permit operation of the set with the antenna in its folded position, where sufficient signal strength is available. As a matter of fact, I have found that it is often possible to receive signals with the antenna folded and the shelf 18 in its closed position, and particularly where the case and panel are of an insulating material and the set is used in a region of high signal strength.

In order to facilitate the use of an auxiliary or external antenna where desired, I have provided a connector, such as the spring clip 50, which is mounted on panel 18 adjacent block 32 but insulated from the panel by the same layer of insulation 48 which supports the block 32. Clip 50 is connected to block 32 through a small condenser 52 whose function is to achieve a more desirable match between a relatively lengthy external antenna and the antenna circuit of the set.

By the above construction I have provided a compact and convenient arrangement of the antenna as well as the power cord (where the set is of the power line operated variety), in that access to both is provided by the single operation of opening closure panel 18. Hence, the effort to gain access to either automatically calls attention to the other, which is a considerable advantage when the set is to be operated by those unfamiliar with the equipment. Moreover, the construction is rugged, reliable and efficient, yet relatively simple and economical to manufacture, and in general satisfies the objects set out at the beginning of this specification.

In accordance with the patent statutes I have described a preferred embodiment of my invention, but I wish it to be understood that the specific terms used and the details disclosed are exemplary only, and that many changes and modifications are possible without departing from the spirit of my invention as defined in the appended claims.

I claim:

1. In portable radio equipment, a case, an aperture in said case, a metallic closure panel hingedly mounted on said case along an edge of said aperture, a rod-like antenna pivotally mounted on the inner side of said closure panel at a point spaced

from the hinge axis thereof, and arranged to pivot about an axis substantially perpendicular to the hinge axis of said panel, a spring clip on said closure panel spaced from the pivot axis of said antenna for releasably retaining said antenna in a position parallel to said panel, and means insulating said antenna and said clip from said panel.

2. In portable radio equipment, a case, a chamber within said case providing stowage room for a power cord, said case being apertured to provide access to said chamber, a closure panel hingedly connected to said case for movement between positions in which it closes the aperture of said case and in which it extends outwardly therefrom, and a rod-like antenna element pivotally mounted upon that surface of said closure panel which faces inwardly of said case when panel is in aperture-closing position, the pivotal mounting of said rod-like antenna element being spaced from the hinge connection between said closure panel and said case, the pivotal axis of said antenna element being substantially perpendicular to the hinge axis of said closure panel.

3. The invention in accordance with claim 2, in which said antenna element is pivotally mounted adjacent one end of said closure panel.

4. In a portable radio equipment, a case, an aperture in said case, a closure panel hingedly mounted on said case along a lower edge of said aperture, means for rigidly holding said closure panel in a substantially horizontal open position, a telescoping rod-like antenna pivotally mounted on the inner side of said closure panel at a point spaced from the hinge thereof, and arranged to pivot about an axis substantially perpendicular to the hinge axis of said panel, said mounting means being so located that when said closure panel is in the open position and said antenna is in a vertical position the antenna is a substantial distance from said case, a spring clip on said closure panel spaced from the pivot axis of said antenna for releasably retaining said antenna in a position parallel to said panel, and means insulating said antenna and said clip from said panel whereby said antenna is electrically operative when held by said clip and said closure panel is in the closed position.
